UNITED STATES PATENT OFFICE.

ROBERT Y. BARROWS, OF RUTHERFORD, AND GEORGE V. STRAHAN, OF NEWARK, NEW JERSEY.

DESIGN FOR A BOWL FOR LIGHTING-FIXTURES.

49,979.

Specification for Design.

Patented Dec. 5, 1916.

Application filed October 3, 1916. Serial No. 123,594. Term of patent 7 years.

To all whom it may concern:

Be it known that we, ROBERT Y. BARROWS, a citizen of the United States of America, residing in the town of Rutherford, in the county of Bergen and State of New Jersey, and GEORGE V. STRAHAN, a citizen of the United States of America, residing in the city of Newark, in the county of Essex and State of New Jersey, have invented a new, original, and ornamental Design for a Bowl for Lighting-Fixtures, disclosed in our earlier application Serial No. 116,739, filed

August 24, 1916, of which the following description, in connection with the accompanying drawing, is a specification.

The single figure of the drawing is an elevation of a bowl for lighting fixtures, showing our new design.

We claim as our invention;

The ornamental design for a bowl for lighting fixtures, as shown.

ROBERT Y. BARROWS.
GEORGE V. STRAHAN.
